TOWEL CABINET

Leo M. Harvey, Los Angeles, Calif.

Application September 13, 1937, Serial No. 163,624

12 Claims. (Cl. 271—2.3)

This invention relates to a dispensing device and relates more particularly to a device for dispensing sheet material such as paper toweling, etc. A general object of this invention is to provide a practical and effective device for dispensing paper toweling that is sanitary and very convenient to use.

Towel dispensing devices of various natures have been introduced. In the majority of prior dispensing devices of this character the user was obliged to turn a crank or engage some other mechanical part with his hands to operate the device in order to receive the toweling. The hands of the user of a towel cabinet are usually wet and the cranks or other manually engaged parts soon became dirty and very unsanitary.

Another object of this invention is to provide a towel dispensing device in which the toweling may be easily obtained or withdrawn from the cabinet without manually engaging mechanical parts such as cranks, levers, buttons or the like.

Another object of this invention is to provide a towel dispensing device in which the edge portion of a sheet or portion of toweling in the case 25 is made accessible for grasping by the user without manually grasping or handling any mechanical parts.

Another object of this invention is to provide a paper towel dispensing device embodying 30 means for automatically ejecting an edge portion of the toweling from the case to be readily grasped by the user for the purpose of withdrawing a towel or length of the toweling.

Another object of this invention is to provide 35 a dispensing device of the character mentioned embodying an effective and dependable means for limiting the amount of toweling that may be withdrawn from the cabinet at each operation.

Another object of this invention is to provide 40 a dispensing device in which the user must perform a series of simple operations or manual acts which operations usually deter the user from obtaining or withdrawing more towels or toweling than required.

45 A further object of this invention is to provide a device of the character mentioned that is substantially tamper proof and that cannot be made inoperative by incomplete or imperfect manual operations.

50 The various objects and features of my invention will be fully understood from the following detailed description of a typical preferred form and application of my invention, throughout 55 which description reference is made to the accompanying drawings, in which:

Fig. 1 is a front elevation of the improved towel cabinet provided by this invention. Fig. 2 is a side elevation of the cabinet. Fig. 3 is an enlarged fragmentary vertical detailed sectional view taken substantially as indicated by line 5 3—3 on Fig. 1 showing the parts in the normal positions. Fig. 4 is an enlarged fragmentary horizontal detailed sectional view taken as indicated by line 4—4 on Fig. 3. Figs. 5 and 6 are fragmentary vertical detailed sectional views 10 taken as indicated by lines 5—5 and 6—6, respectively, on Fig. 4. Fig. 7 is a fragmentary vertical detailed sectional view taken as indicated by line 7—7 on Fig. 4. Fig. 8 is a view similar to Fig. 5 illustrating the dogs and adjacent parts 15 of the ejecting means in the operative positions. Fig. 9 is a view similar to Fig. 6 showing the latch means in the operative condition where the stop means is released immediately preceding 20 the ejecting operation. Fig. 10 is a view similar to Fig. 6 showing the parts in position immediately following the ejecting operation. Fig. 11 is an enlarged fragmentary horizontal detailed 25 sectional view taken as indicated by line 11—11 on Fig. 3, and Fig. 12 is a reduced elevation view of a portion of the toweling.

The present invention may be embodied in forms for handling or dispensing sheet materials of various sizes, characters, etc. In the following 30 detailed description, I will describe a form of the invention intended primarily for dispensing paper towels or paper toweling of the general character described in Patent No. 2,023,357, issued December 3, 1935. It is to be understood that the invention is not to be construed as limited or restricted to the specific form or application of the invention about to be described, but is to be taken as including any features or modifications 35 that may fall within the scope of the claims.

The towel dispensing device of the invention illustrated in the drawings includes, generally, a cabinet or case 10 adapted to hold a supply S of toweling T, a control member 11 in the case 10 having controlling engagement with a portion 40 of the toweling T, means 12 normally tending to operate or move the member 11 to eject an edge portion of the toweling T from the case 10 for grasping by the user, stop means 13 normally preventing movement or operation of the member 11 in a direction to eject the toweling T from the case 10 and governed by cooperation with the toweling T to limit the withdrawal of the toweling, and means 14 actuated by manual movement of the member 11 for releasing the 45 50 55 55

stop means 13 and to allow operation of the toweling ejecting means 12.

The cabinet or case 10 of the device is in the nature of a hollow structure for carrying and housing the various other elements and parts. In the form of the invention illustrated the case 10 is adapted to be arranged or secured on a vertical support such as a wall or the like. The case 10 is constructed so that the supply S of toweling T may be readily arranged within it. The case 10 includes two sections, namely a rear section A and a front section B. The sections A and B are preferably formed of sheet metal and may be finished as desired.

15 The case section A comprises a back 15 and a bottom 16. The back 15 is substantially vertical and the bottom 16 is substantially horizontal and projects forwardly at the lower edge of the back 15. A forwardly projecting flange 17 extends 20 along the vertical edges and the top edge of the back 15 and a similar up-turned flange 18 extends along the side edges of the bottom 16. The section A is provided with supports or plates 19 and 20 for carrying the mechanism of the device and 25 includes a shelf 21 for carrying the supply S of toweling T. In practice the plates 19 and 20 are substantially vertical and project forwardly from the back 15 and upwardly from the bottom 16. The lower edge portions of the plates 19 and 20 30 are welded or otherwise fixed to the flanges 17 and 18 and the rear edge portions of the plates are secured to the back 15. The plate 18 has a shoulder 22 spaced between its upper and lower ends whereby its lower portion is offset laterally or toward 35 the adjacent side of the cabinet. The lower portion of the plate 20 may be similarly offset. Outturned flanges 23 may be provided along the forward edges of the plates 19 and 20. The shelf 21 for carrying the supply S projects forwardly 40 from the back 15 and is located between the two plates 19 and 20. In practice the shelf 21 may have suitable edge flanges rigidly secured to the back 15 and the plates 19 and 20 by welding or the like. In the preferred construction the shelf 45 21 inclines downwardly and forwardly. The forward edge of the shelf 21 is spaced some distance rearwardly from the plane of the forward edges of the plates 19 and 20.

50 The case section B is a rigidly assembled unit connected or associated with the section A so that it may be removed or swung forwardly away from the section A to give free access to the interior of the case. The section B includes sides 55 24, a top 25 and a front. The sides 24 are flat and substantially vertical and the top 25 is normally substantially horizontal. The front of the section B preferably has the characteristic shape illustrated in the drawings. As best shown in 60 Figs. 1 and 2, the front of the case section B has an upper portion 26 bowed downwardly and outwardly from the top 25 and then downwardly and inwardly to join a portion 27 which is bowed downwardly and outwardly and then downwardly and inwardly. The front portion 27 preferably 65 has a smaller radius of curvature than the front portion 26. A flat front portion 28 extends downwardly from the portion 27. The lower edge part of the portion 28 is preferably inclined downwardly and rearwardly. The case section B is 70 preferably hinged or pivoted to the section A so that it may be swung downwardly and forwardly to an open position. In the construction illustrated the section B is pivotally supported by pins 75 29 carried by the section A. The flanges 18 of

the section A are provided with brackets 30 for supporting the pivot pins 29. The brackets 30 extend outwardly or laterally from the flanges 18 so that the adjacent sides 24 of the section B are spaced outwardly from the plates 19 and 20. A latch or lock 31 is provided to hold the section B in its up or closed position illustrated throughout the drawings.

The case 10 is provided with an outlet opening or discharge opening 32 through which the toweling T is ejected and withdrawn. The lower edge of the front portion 28 of the case section B is in a plane above the bottom 16 and the forward edge of the bottom 16 is spaced rearwardly from said front portion 28 leaving the discharge opening 32 in the lower forward corner of the case 10. The bottom 16 may have an upwardly projecting apron 33 at the rear of the opening 32 to assist in guiding the toweling T through the opening. In accordance with the invention the case 10 20 has an access opening 34 through which the user may engage, press against, or manipulate the toweling T engaged or trained over the control member 11. The opening 34 is provided in the front of the section B and is preferably provided 25 in its portion 27. The opening 34 may be rectangular in front elevation and may have its upper and lower edges substantially coincident with the upper and lower margins of the front portion 27. It is preferred to make the opening 34 30 comparatively large. It is to be noted that the access opening 34 is spaced above the discharge opening 32.

35 The supply S of toweling T is supported on the shelf 21 and the toweling T is trained downwardly from the supply S past the access opening 34 toward the discharge opening 32. The toweling T is fibrous absorbent sheet material or paper and in the particular application of the invention illustrated the toweling is supplied to the case 10 40 in the form of a continuous elongate strip wound or rolled into a roll which constitutes the supply S. The roll or supply S is supported on the shelf 21 between the plates 19 and 20 and the plates 45 operate to limit endwise movement of the supply. The strip of toweling T is weakened along spaced transverse lines to readily tear or part along these lines and thus form a multiplicity of individual towels. As illustrated in Fig. 12 of the drawings 50 the strip of toweling T has longitudinally spaced transverse rows of perforations 35 which weaken the strip for ready separation into separate towels. Each towel of the strip, that is, each portion of the toweling T between adjacent lines of 55 perforations 35 has a perforated zone or weakened zone 36. In the toweling T illustrated the zones 36 have multiplicities of adjacent openings or slits whereby they are readily penetrable. The penetrable weakened zones 36 are adjacent 60 one longitudinal edge of the strip of toweling T and each zone 36 is adjacent a line of perforations 35. The several weakened zones 36 of the strip of toweling T are in the same or corresponding positions with relation to the adjacent lines 65 of perforations 35 and the adjacent longitudinal edge of the strip of toweling. The spaced transverse lines of perforations 35 and the spaced penetrable weakened zones 36 are provided throughout the length of the strip of toweling T. 70 The roll or supply S of toweling rests on the inclined shelf 21 and the strip of toweling T is trained from the lower side of the supply past or over the control member 11, as will be subsequently described.

The control member 11 is supported in the case 10 to have movement controlling engagement with the portion of toweling T extending from the roll or supply S to the discharge opening 32. The control member 11 is positioned and mounted to be manually movable through the medium of toweling T accessible through the access opening 34 to control the releasing means 14. The control member 11 is also acted on or moved by the means 12 to effect the ejection of the lower edge portion of the strip of toweling T through the opening 32 to be readily grasped by the user and is controlled by the means 13 to limit withdrawal of the toweling.

In the preferred form of the invention the control member 11 is in the nature of a rotatable element or roller. The control member 11 is elongate and is arranged horizontally in the front portion of the case 10 to protrude into the concave rear side of the outwardly bowed front portion 27. The control member 11 is generally cylindrical and may be formed of wood or the like. It is preferred to cover the periphery of the control member 11 with rubber 9 or similar material to have the desired frictional contact with the toweling T.

In the preferred construction the control member 11 is provided with a shaft 37 which projects from its opposite ends. The control member 11 is supported by the plates 19 and 20 for rotation about a substantially horizontal axis. Bearings 38 are provided on the plates 19 and 20 and rotatably receive the projecting end portions of the shaft 37 to support the member 11 for rotation. The shaft 37 projects outwardly or laterally beyond the bearings 38. The bearings 38 are carried by the laterally offset lower portions of the plates 19 and 20. The circumference of the rotatable control member 11 is concentric with and in close relation to the inner surface of the bowed front portion 27 of the case. The control member 11 is preferably provided with longitudinally spaced circumferential grooves 39 for the purpose to be hereinafter described.

The control member 11, rotatably supported as just described projects upwardly beyond the forward edge of the inclined shelf 21 so that the roll or supply S resting on the forward portion of the inclined shelf bears on and is partially supported by the member 11. The strip of toweling T leaves the supply S at the point or zone of contact between the supply S and the member 11 so that it cannot buckle or become bunched under the supply. The weight or a portion of the weight of the roll or supply S of toweling T maintains the circumferences of the member 11 and the supply S in geared or driving cooperation so that rotation of the member 11 results in rotation of the supply S. The toweling T is trained downwardly over the forward face of the control member 11 to extend between the periphery of the member and the inner surface of the front portion 27. The portion 27 of the case front may have indented parts which form vertical ridges 40 entering the grooves 39 in the member 11 at opposite sides of the access opening 34 to assist in holding the toweling T in cooperation with the member 11 and to prevent the toweling from becoming fouled between the member 11 and the internal surface of the portion 27.

It is to be observed that the toweling T trained across the periphery of the member 11 has a

portion accessible to the user through the opening 34 and that the portion of toweling thus accessible is dependably supported or backed up by the member 11 so that the user may apply force to it to move or turn the member 11. In accordance with the invention the access opening 34 has a horizontal dimension considerably less than that of the strip of toweling T so that the opposite side or edge portions of the toweling T cannot be engaged or grasped through the opening 34. This is important as it prevents the user from gripping or engaging the toweling T at the opening 34 in an attempt to withdraw the toweling through the opening. The access opening 34 is of substantial vertical extent so that the user may readily act on the curved or convex portion of the toweling T exposed at the opening to effect turning of the member 11.

A roller 41 is provided below the member 11 to assist in maintaining the toweling T in cooperation with the member 11 and to assist in directing the toweling through the opening 32. The roller 41 may be a cylindrical member of wood or the like of substantially the same length as the member 11. The roller 41 is supported between the spaced plates 19 and 20 of the case 10. Slots 42 are provided in the plates 19 and 20 in substantially vertical alignment with the bearings 38. Trunnions 43 project from the opposite ends of the roller 41 and extend into the slots 42. The trunnions 43 are rotatable and vertically shiftable in the slots 42. The toweling T is trained between the lower peripheral surface of the member 11 and the upper peripheral surface of the roller 41 and means is provided for urging the roller upwardly so that the toweling is held or firmly engaged between the member and the roller. Springs 44 are connected with the projecting end portions of the trunnions 43 and have their upper ends connected with the projecting portions of the shaft 37 to yieldingly urge the roller 41 upwardly whereby the toweling T is firmly engaged between the member 11 and the roller. The apron 33 may have fingers 45 and the shelf 21 may have fingers 46 which fingers 45 and 46 extend into the grooves 39 in the member 11 to prevent the toweling T from wrapping about the member 11 and from becoming fouled on the member.

The means 12 is provided to advance or feed the toweling T to project the lower edge portion of the toweling through the opening 32 for ready grasping by the user. The ejecting means 12 is automatic. That is, it does not require the manual manipulation of any mechanical parts for its actuation. The automatic ejecting means 12 is operable to move or turn the control member 11 to effect the outward feeding of the toweling T and operates following actuation of the manual control means 13 and thus may be said to be released by actuation of the means 14.

The means 12 includes a sleeve 48 freely turnable on an end portion of the shaft 37. The sleeve 48 is rotatable in the bearing 38 carried by the plate 19 and operates to support the end portion of the shaft 37 in said bearing. In the preferred construction the sleeve 48 projects outwardly beyond the bearing 38 and projects in- 70wardly at the inner side of the supporting plate 19. The means 12 further includes a crank 49 fixed to or integral with the outer projecting portion of the sleeve 48 to turn with the sleeve. The outer end of the crank 49 carries a pin 50 and 75

a link 51 is pivoted on the pin 50. An extensible coiled spring 52 has one end secured to the outer end of the link 51 and has its other end secured to the back 15. The spring 52 is preferably of substantial length. It is believed that it will be understood how rotation of the crank 49 is operable to elongate the spring 52 to store energy therein and how the spring 52 acting on the link 51 and the crank 49 is operable to expend its energy in turning the crank. The turning of the crank 49 by the spring 52 effects turning of the member 11 through the mechanism to be subsequently described.

The means 12 further includes a ratchet drive or escapement drive between the control member 11 and the sleeve 48 whereby the energy of the spring 52 serves to turn the member 11 to feed the toweling T from the case 10 during one phase of operation of the device and turning of the roll member 11 by manual manipulation of the toweling T serves to elongate the spring 52 and store energy therein for a subsequent operation during another phase of operation of the device. This ratchet drive includes a ratchet wheel 53 between the plate 19 and the adjacent end of the member. The wheel 53 has a tubular hub 53^a which is secured to the member 11 as will be hereinafter described. The wheel 53 has substantially square peripheral teeth 54. The ratchet drive further includes a disc 55 fixed to the sleeve 48 at its inner end to be immediately adjacent the ratchet wheel 53. Two ratchet dogs 56 and 57 are pivoted on the disc 55 to cooperate with the ratchet wheel 53. Spaced pins 58 on one side of the disc 55 pivotally support the dogs 56 and 57. The dogs 56 and 57 are positioned so that their heads cooperate with the toothed ratchet wheel 53 at substantially diametrically opposite points. The head of the dog 56 is adapted to cooperate with the teeth 54 to form a driving connection between the crank 49 and the member 11 to effect turning of the member 11 and ejection of the lower edge portion of the toweling T under the force exerted by the spring 52. The head of the dog 57 is adapted to cooperate with the teeth 54 of the wheel 53 to transmit turning force from the member 11 and the wheel 53 to the crank 49 to stretch the spring 52 and thus store energy therein for the next ejecting operation. A spring wire 59 is wrapped about a pin 60 on a side of the disc 55 and cooperates with the tail portions of the dogs 56 and 57 to urge the heads of the dogs into cooperation with the teeth 54 of the wheel 53.

The ejecting means 12 includes a control for holding its parts in the position illustrated in Fig. 5 of the drawings where the spring 52 is maintained under tension. The said control includes an abrupt shoulder 61 on the periphery of the disc 55 and a pivoted lever 62 having a finger 63 for cooperating with the shoulder 61. The lever 62 may be yoked or of inverted U-shape in cross section and the finger 63 may be provided on one side part of the U-shaped lever. A pin 64 passes through openings in the lower portions of the spaced side parts of the lever 62 to pivotally support the lever. The pin 64 has one end portion carried in an opening in the plate 19 and has its other portion carried in an opening in a bracket 65 projecting from the bottom 16. The lever 62 has a depending arm 66 and a spring 67 is connected to the arm 66 to yieldingly maintain the lever 62 in a position where its finger 63 is in cooperation with the shoulder 61. The finger 63 cooperating with the shoulder 61 holds

the disc 55 against turning when the spring 52 is under tension or is elongated in which condition the spring tends to turn the member 11 in a direction to feed the toweling T from the opening 32. The stop finger 63 is released from the shoulder 61 by the release means 14 as will be subsequently described to allow the spring 52 to turn the control member 11 and thus eject the edge portion of the toweling T through the opening 32. The rear end of the spring 67 may be connected to a stationary lug 67^a on the plate 19.

The ejecting means 12 includes a control for holding the dog 57 released from the ratchet wheel 53 when the toweling T is being manually withdrawn from the case 10 after the spring 52 has been elongated by the action of the crank 49, the dog 57 being released at this time allows continued rotation of the control member 11 following the full conditioning or elongation of the spring 52. The control means for the dog 57 includes a cam face 68 on the tail portion of the dog 57 and a cylindrical roller 69 for cooperating with the face 68. In practice the roller 69 may be rotatable on the pin 64 between the spaced side parts of the U-shaped lever 62. The roller 69 cooperates with the face 68 to free the head of the dog 57 from the ratchet wheel 53 when the shoulder 61 cooperates with the finger 63 so that this cooperation does not stop rotation of the member 11 and limit withdrawal of the toweling T from the case 10.

The operation of the above-described automatic ejecting means 12 is dependent upon the rotation of the control member 11 by manual withdrawal of the toweling T from the case 10 and is dependent upon manual actuation of the release means 14, the rotation of the member 11 by the manual withdrawal of the toweling operating to elongate the spring 52 to store energy therein and the actuation of the means 14 operating to initiate the ejecting function of the means 12. The operation of the several parts of the means 12 will be subsequently described in conjunction with the operation of the other elements of the machine.

The stop means 13 operates to limit the withdrawal of the toweling T from the case 10 and in accordance with the invention is in the nature of a brake means for stopping rotation of the control member 11 in the towel dispersing or discharging direction indicated by the arrow X throughout the drawings. It is a feature of the invention that the stop means 13 is governed by cooperation with the toweling T. The means 13 includes a brake 70 for cooperating with the rubber 9 on the periphery of the control member 11. The brake 70 is a U-shaped member supported in the case 10 for pivotal movement. In the construction illustrated a pin 71 is carried by a suitable bracket 72 on the under side 60 of the shelf 21 and passes through openings in the spaced parts of the U-shaped brake 70 to pivotally support the brake. The brake 70 is positioned at the rear of the control member 11 and its axis of pivotal movement is spaced above the 65 plane of the axis of rotation of the member. A brake shoe 73 of rubber or the like is provided on the forward end or forward part of the brake 70 to cooperate with the rubber 9 on the control member 11. Because of the location of the brake 70 and the position of its axis of pivotal movement the brake is operable to effectively bind against the peripheral rubber 9 of the control member 11 to stop rotation of the member in the direction indicated by the arrow X. When the 75

shoe 73 of the brake 70 is engaged against the rubber 9 of the member 11 and the member is turning or is tending to turn in the direction indicated by the arrow X, the brake pivots upwardly and thus forms a toggle between its pivot pin 71 and the peripheral rubber 9 of the member 11 to definitely stop turning of the member. The stop means 13 further includes a towel engaging element 74 for governing the brake 70. The element 74 has two spaced side parts 75 and is supported for pivotal movement about a substantial horizontal axis. In practice the element 74 may be pivotally supported by the pin 64 between the bracket 65 and the lever 62. The pin 64 may pass through openings in the side parts 75 of the element 74 to pivotally support the element. The element 75 is operatively connected with the pivoted brake 70. In the simple construction illustrated a lug 76 on a side part 75 of the element 74 passes through an opening 77 in a side part of the U-shaped brake 70 to operatively connect the element 74 with the brake so that pivoting of the element effects pivoting of the brake. The element 74 is preferably spring urged or spring held. An arm 78 projects downwardly from one side part 75 of the element 74 and a spring 79 is connected with the lower end of the arm 78 to urge the arm rearwardly and thus urge the side parts 75 of the element 74 forwardly. The rear end of the spring 79 may be connected with a clip or lug 80 on the supporting plate 19. It is believed that it will be understood how the spring 79 urging the side parts 75 of the element 74 forwardly tends to pivot the brake 70 forwardly and upwardly into cooperation with the peripheral rubber 9 of the control member 11. The parts are related so that the brake 70 normally inclines downwardly and forwardly with respect to its pivot pin 71 so that the lug 76 on the spring urged element 74 tends to pivot the brake 70 forwardly and upwardly to bring its shoe 73 against the peripheral rubber 9 of the control member 11.

penetrable zones 36 in the toweling T, the finger 81 and the aligned grooves 39 and 83 are located and related so that the zones 36 pass between the grooves 39 and 83 when the towels or lengths of toweling are successively withdrawn from the case 10. The spring 79 acting on the element 74 yieldingly urges the finger 81 downwardly against the toweling T and when a penetrable zone 36 moves between the control member 11 and the roller 41 the finger 81 is urged through or penetrates the zone. The finger 81 of the spring urged element 74 penetrating the zone 36 under the action of the spring 79 allows or is accompanied by pivoting of the element 74. The lug 76 cooperating with the opening 77 in the brake 70 transmits the pivotal movement from the element 74 to the brake 70 so that pivoting of the element when its finger 81 penetrates a zone 36 effects setting or operation of the brake 70. Fig. 6 of the drawings illustrates the finger 81 passing through a penetrable zone 36 of the toweling T and shows the brake 70 in its set or holding position. As described above, the brake 70 toggles or binds against the rubber 9 of the member 11 to dependably stop rotation of the member in the direction indicated by the arrow X and thus definitely limits the withdrawal of the toweling T. The cooperation of the brake shoe 73 with the rubber 9 on the member 11 of course limits pivoting of the element 74 and stops the element in a position where its finger 81 is clear of the walls of the groove 83 so that the spring 79 continues to exert an actuating or holding force on the brake 70. The transverse lines of perforations 35 are related to the penetrable zones 36 so that a line of perforations 35 is adjacent or slightly below the roller 41 when the outward movement or withdrawal of the toweling T is stopped concurrently with the entrance of the finger 81 in a zone 36. In practice the lowermost line of perforations 35 in the strip of toweling T is spaced above the mouth of the discharge opening 32 when the brake 70 operates to stop

Set 9 of the control member 11. Movement of the brake controlling element 74 is governed by cooperation of the element with the towelling T whereby the brake 70 is set when a predetermined length of towelling T has been withdrawn from the case 10. One side part 75 of the element 74 has a forwardly projecting finger 81. The forward end of the finger 81 is rounded or convex being curved downwardly and rearwardly from the top of the finger to the lower end of the finger to cooperate with the towelling T without tearing or biting into the towelling. The lower edge 82 of the finger 81 is concaved to bear downwardly on the portion of towelling T passing over the roller 41. The forward edge and the lower edge 82 of the finger 81 are preferably broadened to have more extensive engagement with the towelling T. The roller 41 is provided with an annular peripheral groove 83 in the same vertical plane as the finger 81 so that the finger cooperates with the towelling T above or at the groove 83 as illustrated in Fig. 10 of the drawings. The upper major portion of the finger 81 which is above the towelling T and the roller 41 is received in one of the grooves 39 in the control member 11.

The engagement of the finger 81 with the toweling T trained over the roller 41 limits pivoting of the element 74, by the spring 79, holding the element 74 in the position where the brake shoe 73 is free of or out of cooperation with the rubber 9 on the control member 11, as illustrated in Fig. 10 of the drawings. The weakened or upwardly and forwardly from its pin 89 and has a finger 90 projecting downwardly to cooperate with the teeth 87 of the disc 85. A weight 91 may be provided on the upper end of the pawl 88 to assist in urging its finger 90 into cooperation with the teeth 87. The upper portion of the pawl 88 and its weight 91 may project through a suit- 75

able opening 92 in the shoulder 22 of the plate 19. The finger 90 is engageable by a tooth 87 so that movement or turning of the control member 11 in the direction indicated by the arrow Y is transmitted to the pawl 88 which in turn transmits the inward or rearward movement to the pivoted lever 62. The user of the towel cabinet may push or bear against the toweling T exposed at the opening 34 to turn the member 11 in the direction indicated by the arrow Y. As just described turning of the member 11 in the direction indicated by the arrow Y results in rearward pivoting of the lever 62. When the lever 62 is moved or pivoted rearwardly in this manner its finger 63 is moved out of engagement with the shoulder 61 to free the lever 62 from the disc 55. Rearward movement or pivoting of the lever 62 resulting from manual turning of the control member 11 in the direction indicated by the arrow Y also pivots the element 74 to release the brake 70 and to withdraw or retract the finger 81. A lug 93 is provided on one of the side parts 75 of the element 74 and is engaged by a side part of the lever 62 when the lever is pivoted rearwardly, as just described, so that rearward pivoting of the lever 62 effects rearward pivoting of the element 74. This rearward pivoting of the element 74 releases the brake shoe 73 from the rubber 9 of the element 11 and retracts the finger 81 from the path of the toweling T so that the ejecting means 12 is free to turn the member 11 and eject the lower edge portion of the toweling T when the user removes his hand or the rearward pressure from the portion of the toweling T accessible at the opening 34.

The release means 14 further includes a latch mechanism for temporarily holding the element 74 in the position where its finger 81 is out of the path of the toweling T and where the brake 70 is released so that the ejecting means 12 is free to eject the lower edge portion of the toweling T following the manual turning of the member 11 in the direction indicated by the arrow Y, as described above. In practice the latch mechanism 40 operates to hold the element 74 in the retracted position until the ejecting means 12 has moved the lowermost penetrable zone 36 past the finger 81 and until the shoulder 61 has moved past the finger 63. The latch mechanism includes a latch 45 94 pivotally supported on the pin 89 and projecting forwardly. The forward end of the latch 94 has two vertically spaced fingers 95 and 96 which straddle a knurled or toothed pinion 97 fixed to the member 11 between the wheel 53 and the disc 85. The pinion 97 may be integral with 50 the wheel 53 and in practice may be an exposed portion of the above described hub 53a. A toothed face or shoulder 98 is provided on the forward end of the latch 94 and extends downwardly from 55 adjacent the upper finger 95. A notch 99 is provided in the forward edge of the latch 94 between the lower edge of the shoulder 98 and the lower finger 96.

65 The vertically spaced fingers 95 and 96 of the latch 94 are adapted to cooperate with the pinion 97 to limit the vertical pivoting movement of the latch. The toothed shoulder 98 is adapted to cooperate with the toothed pinion 97 to temporarily hold the latch 94 in its active or latching position. The cooperation of the shoulder 98 with the pinion 97 holds the latch 94 in a position where the latch temporarily retains the lever 62 and the element 74 in retracted positions with the finger 63 out of cooperation with the shoulder 61 and with the finger 81 out of the

path of movement of the toweling T and with the brake 70 released. When the parts are in their normal or initial positions the pinion 97 is received in the notch 99 of the latch 94. When the lever 62 is pivoted rearwardly through the cooperation of the pawl finger 90 with a tooth 87 by the turning force exerted on the member 11 by the user acting on the toweling T at the access opening 34, the latch 94 moves rearwardly with the lever to a position where the shoulder 98 is immediately behind the pinion 97. This allows the latch 94 to pivot downwardly by gravity until its upper finger 95 engages the pinion 97. When the latch 94 falls or pivots downwardly the spring 67 acting on the lever 62 urges the latch 94 forwardly so that the teeth of the shoulder 98 cooperate with the teeth of the pinion 97. It will be understood how the toothed shoulder 98 cooperating with the pinion 97 holds the lever 62 in a position where the finger 81 is out of the path of the toweling T, the brake 70 is released and the finger 63 is out of engagement with the shoulder 61. Immediately upon the disengagement of the finger 63 from the shoulder 61 and the release of the manual force or pressure from the control member 11 the spring 52 exerting a turning force on the crank 49 turns the member 11 in the direction indicated by the arrow X to advance the toweling T and project the lower edge portion of the toweling through the opening 32. The spring 52 continues to turn the control member 11 and thus effect the ejection of the toweling T until the crank 49 and the link 51 assume positions in longitudinal alignment with the spring 52, as shown in Fig. 8 of the drawings. During the turning of the control member 11 by the spring 52 of the ejecting means 12 the teeth of the shoulder 98 and the pinion 97 mesh to effect upward pivoting of the latch 94. This upward pivoting of the latch 94 continues until the notch 99 receives the pinion 97. When the notch 99 receives the pinion 97 the latch 94 and the lever 62 move forwardly under the action of the spring 67 freeing the lever 62 from the lug 93 and bringing the finger 81 into engagement with the toweling T. The ejecting means 12 will have advanced the toweling T to move the lowermost penetrable zone 36 past the finger 81 when the finger returns into engagement with the toweling T at the release of the means 14, as just described. As previously described, the cooperation of the finger 81 with the toweling T holds the brake 70 released so that the user may grasp the ejected lower edge portion of the toweling T and freely withdraw the toweling from the case 10 until the finger 81 penetrates a weakened zone 36 to effect the operation of the brake means 70.

In operation it will be assumed that the parts are in the positions illustrated in Figs. 1 to 7, inclusive, of the drawings where the lower edge of the toweling T is some distance above the mouth of the discharge opening 32, the finger 81 is extending through the lowermost weakened zone 36 of the toweling T, the brake is in cooperation with the rubber 9 of the member 11, the spring 52 is held elongated or under tension, the means 14 is released and the pawl 88 is in cooperation with the toothed ratchet wheel 85. It will be observed that the toweling T cannot be grasped or engaged at the opening 32 and that the edges of the toweling T cannot be grasped at the access opening 34 so that the user cannot obtain or attempt to obtain the 75

toweling T without first acting on the exposed portion of toweling T in the opening 34 in the prescribed manner to release the stop means 13.

To effect the automatic ejection of the toweling T through the discharge opening 32 the user must apply pressure or force to the portion of the toweling T exposed at the opening 34 in a manner to turn the control member 11 in the direction indicated by the arrow Y. When the member 11 is turned in the direction indicated by the arrow Y a tooth 87 of the wheel 85 cooperates with the finger 90 of the pawl 88 to shift the pawl and the lever 62 rearwardly. The lever 62 moving rearwardly engages the lug 93 so that the element 74 is moved rearwardly with the lever to retract the finger 81 from the path of the toweling T and to release the brake 70 and to allow the latch 94 to move downwardly by gravity to the position where its shoulder 98 may cooperate with the pinion 97 to gear the latch to the pinion 97 for upward swinging. The finger 63 of the pivoted lever 62 is released from the shoulder 61 of the disc 55 substantially simultaneously with the release of the stop means 13 and the latching of the latch 94.

The release of the finger 63 from the shoulder 61 conditions or frees the ejecting means 12 for operation and when the user removes his hand or hands from the portion of the toweling T exposed at the opening 34 the spring 52 acting on the crank 49 turns the member 11 in the direction indicated by the arrow X and the member serves to feed the toweling T downwardly so that its lower edge portion is ejected through the discharge opening 32. The turning force is transmitted from the assembly of the crank 49 and the disc 55 to the wheel 53 secured to the member 11 through the medium of the dog 56 cooperating with a tooth 54. The spring 52 of the ejecting means 12 operates to turn the control member 11 to feed the toweling T downwardly until the crank 49 assumes a position in axial alignment with the spring 52. In practice the ejecting means 12 operates to feed the toweling T downwardly to have a substantial portion project from the case 10 at the discharge opening 32 for ready grasping, as illustrated in Fig. 10 of the drawings.

During the towel ejecting operation of the means 12 just described the pinion 97 cooperates with the toothed shoulder 98 to pivot the latch 94 upwardly. Before the automatic towel ejecting operation is complete the latch 94 reaches the position illustrated in Fig. 10 of the drawings where the notch 99 receives the pinion 97. Upon the forward shifting of the latch 94 to this position under the action of the spring 67 the lever 62 moves forwardly away from and out of cooperation with the lug 93 allowing the element 74 to pivot under the action of the spring 79 to a position where its finger 81 engages the toweling T. The engagement of the finger 81 with the toweling holds the element 74 in a position where the brake 70 is out of cooperation with the member 11, as described above. The above described forward movement of the lever 62 brings its finger 63 to a position in the path of movement of the shoulder 61 of the disc 55. Thus when the ejecting operation is completed the stop means 13 is released so that the user may grasp the projecting portion of the toweling T and withdraw the toweling from the case 10.

The manual manipulation or withdrawal of the toweling T from the case 10 causes rotation of the control member 11 in the direction indicated by

the arrow X, the toweling T engaging about the member 11 drives or turns the member. During this rotation of the control member 11 the dog 57 cooperates with the tooth 54 of the wheel 53 to cause rotation of the disc 55 and the crank 49 with the control member. Turning of the crank 49 elongates or stretches the spring 52 storing energy therein. In practice the crank 49 turns to a position such as illustrated in Fig. 5 of the drawings. During this turning of the crank 49 the face 68 of the dog 57 cooperates with the roller 69 and causes pivoting of the dog to a position where it is released from the teeth 54 of the wheel 53. Substantially simultaneous with the release of the dog 57 the shoulder 61 comes into cooperation with the finger 63 of the lever 62 to prevent further turning of the disc 55 and to maintain the elongated spring 52 under tension. Thus the disc 55 and the crank 49 are freed from the rotating control member 11 and the wheel 53 so that the control member 11 may continue to rotate after the shoulder 61 comes into engagement with the stop finger 63. The teeth 54 ratchet past the dog 56 during rotation of the member 11 in the direction indicated by the arrow X. It will be noted that the turning of the control member 11 and the associated parts effects elongation of the spring 52 and the storing of energy in the spring when the user pulls or withdraws the toweling T from the case 10.

The user may continue to withdraw the toweling T from the case 10 until the second to the lowermost weakened zone 36 in the toweling enters between the control member 11 and the roller 41 whereupon the finger 81 urged by the spring 79 penetrates said zone 36. As described above, the entrance of the finger 81 in a weakened zone 36 is accompanied by forward movement of the element 74 and the brake 70 so that the shoe 13 of the brake comes into braking or stopping cooperation with the rubber 9 on the control member 11. This, of course, stops rotation of the control member 11 and definitely limits withdrawal of the toweling T from the case 10. The user may then exert a downward or outward pull on the withdrawn portion of the toweling T to part said portion of the toweling from the strip of toweling 10 in the case along the lowermost line of perforations 35. In practice the stop means 13 operates to limit the withdrawal of the toweling T and to stop the toweling in a position where the lowermost line of perforations 35 is above the mouth of the opening 32. Accordingly, when the withdrawn portion of toweling is pulled or torn free the lower edge of the toweling T remaining in the case 10 is hidden in the case and is inaccessible or very difficult of access. From the above it will be seen that the manual withdrawal of the toweling T from the case 10 automatically sets up or conditions the ejecting means 12 for a subsequent operation and automatically actuates the stop means 13 to definitely limit the amount of toweling that may be withdrawn at that operation. Following the tearing free of the withdrawn portion of toweling T the device is in condition for operation.

Having described only a typical preferred form and application of my invention, I do not wish to be limited or restricted to the specific details herein set forth, but wish to reserve to myself any variations or modifications that may appear to those skilled in the art or fall within the scope of the following claims:

Having described my invention, I claim:

1. A paper towel dispensing device comprising

- a case for holding a supply of paper toweling, the case having a discharge opening and an access opening through which a portion of the toweling is accessible, spring means in the case operable 5 to eject an edge portion of the toweling through the discharge opening to be engaged by the user whereby the user may withdraw toweling from the case, releasable means holding the spring means against operation and released by manipulation of the toweling accessible through the access opening, and means operable by the force applied to the toweling to withdraw the toweling for conditioning the spring means for the succeeding ejecting operation.
- 15 2. A paper towel dispensing device comprising a case for holding a supply of paper toweling, the case having a discharge opening, means in the case operable to eject an edge portion of the toweling through the discharge opening whereby 20 the user may withdraw toweling from the case, releasable means holding the first mentioned means against operation, releasable brake means for stopping withdrawal movement of the toweling to limit the withdrawal of the toweling, and 25 means operable by the user for substantially simultaneously releasing the two releasable means whereby the said first mentioned means may eject an edge portion of the toweling for a second withdrawal operation.
- 30 3. A towel dispensing device comprising a case for containing a supply of toweling, the case having a discharge opening, a control member in the case having movement producing and controlling engagement with the toweling, spring means in 35 the case for operating the member to advance a portion of the toweling to protrude from said opening to be grasped for withdrawal, means operable by the force applied to the toweling during such withdrawal for conditioning the spring 40 means for a subsequent operation, releasable means normally holding the spring means against operation, releasable means governed by engagement with the toweling operable to stop said member to limit the withdrawal of the toweling 45 and releasable by the user, and an operative connection between the two said releasable means whereby the release of the limiting means is accompanied by operation of the spring means.
4. A towel dispensing device comprising a case 50 for containing a strip of toweling, the case having a discharge opening and an access opening through which a portion of toweling is accessible to the user for manipulation, a turnable member in the case having movement controlling engagement with the toweling and turnable by manipulation of said portion of the toweling, releasable means for holding the member against turning, means operable by turning of the member by such manipulation of said portion of the toweling 55 60 for releasing the releasable means, and means in the case for turning the member after the release of the releasable means to eject a portion of the toweling from the discharge opening.
5. A device of the character described comprising a case for containing a supply of toweling and having an outlet opening, a member in the case movable by and having movement controlling engagement with the toweling, means in the case for moving the member to feed a portion of the toweling out through said opening to be 65 70 grasped by the user whereby the user may withdraw the toweling from the case, means operable by movement of the member during the withdrawal of the toweling for energizing the first mentioned means for a succeeding operation,

releasable means governed by cooperation with the toweling for stopping movement of the member to limit the withdrawal of the toweling, and means for releasing the said releasable means.

6. Apparatus of the character described including a case for housing a strip of toweling, the case having a discharge opening and having an access opening through which a portion of the strip may be engaged by the user, a movable control member in the case mounted to be movable by manual manipulation of the said portion of the strip and having movement controlling engagement with the strip, means in the case for moving the control member to eject a part of the strip from the discharge opening to be grasped by the user, and means holding the last mentioned means against operation released by manual movement of the control member through the medium of said portion of the strip.

7. Apparatus of the character described including a case for housing a strip of toweling, the case having a discharge opening and having an access opening through which a portion of the strip may be engaged by the user, a movable control member in the case mounted to be movable by manual manipulation of the said portion of the strip and having movement controlling engagement with the strip, means in the case for moving the control member to eject a part of the strip from the discharge opening to be grasped by the user for the purpose of withdrawing the strip from the case, releasable restraining means holding the member against movement, and means operable by manual movement of the control member through the medium of the said portion of the strip for releasing the said restraining means.

8. In combination, an elongate supply of paper having penetrable zones at longitudinally spaced points, a case housing said supply and having a discharge opening, spring actuated means in the case for advancing the paper to eject a portion of the paper from the opening, and means for limiting the outward movement of the paper including a movable part engaging the paper and adapted to penetrate said zones, and means for stopping movement of the paper actuated upon movement of said part through a said zone.

9. In combination, an elongate supply of paper having penetrable zones at longitudinally spaced points, a case housing said supply and having a discharge opening, spring driven means in the case for advancing the paper to eject a portion of the paper from the opening, brake means for restraining outward movement of the paper, and means for initiating operation of the brake means comprising a part adapted to penetrate one of said zones.

10. A device of the character described comprising a case for containing a supply of toweling and having an outlet opening, a rotatable member in the case having movement controlling engagement with the toweling, means in the case for turning the member to feed a portion of the toweling through said opening to be grasped by the user, and means for limiting the withdrawal of the toweling from the case, the last mentioned means comprising a pivoted brake having a shoe for cooperating with a peripheral surface of the member, and means for bringing the shoe into cooperation with the member.

11. A paper towel dispensing device comprising a case for holding a supply of paper toweling, the case having a discharge opening, means in the case operable to eject an edge portion of the toweling through the discharge opening whereby

the user may withdraw toweling from the case, releasable means for holding the first mentioned means against operation, means for limiting the withdrawal of toweling from the case including a brake, power means for operating the brake, and a part for engaging the toweling and adapted to act in conjunction with the power means to operate the brake, means operable by manipulation of the toweling for releasing said releasable means, for releasing the brake, and for conditioning said part to have brake operating engagement with the toweling, and means operable by the withdrawal of the toweling for conditioning the first mentioned means for the succeeding operation.

12. A towel dispensing device comprising a case

for containing a strip of toweling, the case having a discharge opening and an access opening through which a portion of the toweling is accessible for manual manipulation, a member in the case having movement controlling engagement with the toweling and movable to feed the toweling, and movable by manual manipulation of said portion, means in the case for moving the member to feed an edge portion of the toweling through the discharge opening, and releasable means for holding the last mentioned means against operation releasable by reverse movement of said member resulting from manual manipulation of said portion of toweling in a reverse direction.

LEO M. HARVEY.
